UNITED STATES PATENT OFFICE.

HERBERT S. ATKINSON, OF EAST ORANGE, NEW JERSEY, ASSIGNOR TO THE HAYWARD COMPANY, OF NEW YORK, N. Y., A CORPORATION OF NEW YORK.

BUCKET.

1,371,291.

Specification of Letters Patent. Patented Mar. 15, 1921.

Application filed June 25, 1915, Serial No. 36,177. Renewed August 2, 1920. Serial No. 400,799.

To all whom it may concern:

Be it known that I, HERBERT S. ATKINSON, a citizen of the United States, and residing at East Orange, in the county of Essex and State of New Jersey, have invented 5 certain new and useful Improvements in Buckets, of which the following is a full, clear, and exact specification, such as will enable others skilled in the art to which it 10 appertains to make and use the same.

This invention relates to an improvement in excavating buckets, and although I have shown the same as applied to a sheave-operated bucket of the clam-shell type, I do 15 not wish to be understood as limiting my invention to the precise form of bucket illustrated in the drawings.

My invention has especial utility in those forms of buckets wherein supporting members are pivotally connected to the upper center or head of the bucket, in spaced-apart relation; also in those forms of bucket wherein the lower center has spaced-apart pivotal connections with the bowl sections or extensions thereof.

In the form of bucket just mentioned, and illustrated in the drawings, wherein the referred to pivotal connecting points are spaced from each other, it is desirable to 30 have some means of holding the parts securely together in operative relation, so that when the bucket is lowered onto the material there will be no danger, especially where the material forms an uneven surface, 35 of the bucket tilting, and the parts being thrown out of their normal relative positions.

One object of my invention is to provide means whereby the relative movements of 40 the supporting members and head are controlled within certain defined limits not only during the normal operation of the bucket upon a substantially even surface, but also when the bucket is operated upon a more or 45 less uneven bed of material. Thereby, the bucket head is not only prevented from tilting, being always maintained in its normal operative position, but the supporting members themselves in operation, are caused to 50 move substantially coincidently with each other.

A further object of my invention is to provide means, at each side of the bucket, at the pivotal connection of the lower center 55 with the bowl sections or their extensions,

whereby the lower center casting is prevented from turning, and is retained in an approximately horizontal position, and whereby also the respective bowl sections, in their oscillating movements, from their pivotal 60 connections with the lower center casting, are caused to move substantially coincidentally with each other. This coincidence of movement in the case both of the upper and lower centers, is desirable, so that both of 65 the bowl sections may operate with the same uniform digging or excavating effect.

A further object of my invention is to provide means for the accomplishment of the objects stated, which shall be economical 70 to manufacture, which is strong and durable, easily and quickly installed, and which will permit of replacement of broken parts with a minimum expenditure of time and labor. Furthermore, which may be readily and 75 quickly adjusted to compensate for wear of the parts, whenever wear necessitates adjustment.

All of these objects will be readily apparent from the following description taken in 80 connection with the accompanying drawings, in which:

Figure 1 is a side elevation of one form of bucket embodying my improvements;

Fig. 2 is an end elevation of same; 85

Fig. 3 is a side elevation in part broken away; and

Fig. 4 is a plan view of a detail, partly broken away.

Referring to the construction illustrated, 90 A indicates in whole, a clam-shell bucket, comprising a head indicated in whole at B, a plurality of bowl sections indicated at C, D, which are pivotally connected to supporting members E, the latter being, in 95 turn, pivotally connected to the head B.

A set of sheaves E' are provided in the head B and a set of sheaves F are provided in the lower center or perpendicularly moving sheave-carrying member indicated at G, 100 to which latter the bowl sections C, D, are also pivotally connected through the pivoted members H, I.

A closing line J passes down through one of the rope thimbles L at one side of the supporting head, downwardly and around one of the outside sheaves in the lower center, upwardly and over the alining outer sheave in the upper center, thence downwardly 110 and around the middle sheave in the lower

center, thence upwardly and around the opposite outer sheave in the upper center, thence downwardly and around the other outer sheave in the lower center, and upwardly and through the other rope thimble on the other side of the supporting head indicated at L. Around the central sheave in the upper center passes a holding rope M, for supporting the bucket. The bucket is 10 opened by slackening off the closing line J, while holding taut the holding line, whereupon the sheave-carrying member G descends, opening the bowl sections. It is 15 closed by hauling in on the closing rope J, drawing the upper and lower centers together.

The head B comprises a casting, formed centrally with a recess to receive therein the sheaves already referred to, and at each side 20 is provided with an outwardly and downwardly projecting hood, indicated at N, the lower portion of which is spaced from the body of the head casting to form a housing for the upper ends of the supporting members E, the latter being pivotally connected to the head by means of the pins O, which pass through the parts N, through the members E, and into and through a flange on the main body of the casting, to which they may 25 be secured in any suitable manner. The upper ends of the supporting members E, have formed thereon and preferably integral therewith, bearing lugs O', O². The supporting members E also have formed thereon, or rigidly secured thereto at their upper ends, holding jaws, each comprising a pair 30 of plates P, P', which jaws are adapted to receive, at the inner lower ends thereof, and to have secured thereto, pivotally, one end 35 of a chain link P², P³, to which are pivotally secured respectively, relatively long links P⁴, P⁵. To the long links P⁴, P⁵, are pivotally connected short links P⁶, P⁷, which latter are formed with curving extensions 40 P⁸, P⁹, adapted to pass through bores in the holding lugs O', O², and to be secured in 45 position by holding nuts P¹⁰, P¹¹, the ends of the extensions P⁸, P⁹ being threaded for the reception of said nuts and also to provide 50 for proper adjustment of the parts. It will be noted that the longer link P⁴ is a single link, and the link P⁵ a double link having a longitudinal inner space through 55 which may pass the single link P⁴, and as both these links are relatively thin, each may move without interfering with the other.

Each of the pivoted members H, I, is provided with a plurality of bearing collars Q, Q', which are more clearly illustrated in Fig. 2. As each of said members H, I, is provided with a similar set of bearing collars, a description of one will suffice for all. These bearing collars, Q, Q', are preferably formed separately from the members H, I, and riveted thereto, one at the inside and one at

the outside, and are formed with a central bore, through which, and through a bore in the end of the pivoted members, H, I, and into a recess in the sheave-carrying member G, passes a pin indicated at R, for holding 70 the parts in proper position. The bearing collars Q, Q', are each formed with a peripheral groove, indicated at S for the reception of the links of a chain indicated at T, T'. The bearing collars Q, Q' are also 75 formed with radially projecting lugs U, which are bored to receive the threaded ends of extensions U' of the chains T, T', which threaded ends are held in properly adjusted position by means of holding nuts U². It 80 will be observed that the holding collars Q, Q' upon the ends of the pivoted members I are directly oppositely disposed to similar bearing collars on the ends of the pivoted members H, the ends of the chains T, T' 85 where secured to the bearing collars on the member I being disposed one downwardly and one upwardly, and those on the member H are likewise disposed one downwardly and one upwardly but in reverse order to 90 the positions of the chain ends fastened to the member I, the relative positions of the chains being such that they may clear each other readily in passing.

The operation will be quite clear without 95 lengthy description. Assuming the parts to occupy the closed position shown in Fig. 1, the closing line J is slackened, and the sheave-carrying member G descends; in its descent the bowl sections open, the pivoted members H, I being given an oscillating movement upon their pivotal connections with the member G, the collars Q rotating toward each other, and in this rotation the chains T will unwind from one of the members Q, winding upon the opposite member Q and the chain T' will wind upon the member Q' and unwind from the opposite member Q'. In this opening movement also the supporting members E have a slight oscillating movement, and in this movement a similar winding and unwinding operation is present in the case of the chain-link-control 100 connected to the upper ends of said members as has just been described for the operation of the chain control upon the ends of the pivoted members. It will be observed that in both these cases the head and the supporting members cannot move in any other manner relatively to each other than 105 is contemplated in the ordinary practical operation of the bucket; extraordinary relative movement, such as might cause tilting of the bucket-head upon the supporting members, is avoided, and the latter must 110 move, in their oscillations, coincidently with each other. The same is true of the movement of the pivoted members H, I. The oscillating movement of one of said members is only such as is permitted by a similar 115

oscillation of the opposing member, since the control chain is taken up by one bearing collar of one pivoted member, to the extent only that it is given up or unwound from the bearing collar on the oppositely disposed member. Thus the pivoted members, and consequently the bowl sections, to which they are connected, must move coincidently with each other both in their opening and 10 their closing movements; and this is true where the operation of the bucket is performed upon a bed of material even or uneven in its surface. The operation of the invention is more clearly illustrated in Fig. 3, 15 wherein the bucket is shown in open position, and wherein will be seen the relative positions assumed by the respective parts as distinguished from their positions indicated in Fig. 1, when the bucket is closed. Furthermore, by my invention, the sheave-carrying member in the lower center is prevented from tilting or turning, and will 20 always occupy a substantially horizontal position, in the operation of the bucket.

I desire it to be understood that I do not confine myself to the precise details of construction and arrangement of the invention herein set forth, as modification and variation may be made without departing from 30 the spirit of the invention, as defined by the appended claims.

What I claim is:

1. In a bucket, the combination with a plurality of supporting members, and a head 35 to which said supporting members are pivotally connected, of a pair of jointed means having operative connection with an adjoining pair of supporting members, and means securing said jointed means to said 40 members adjacent their pivotal connections with the head adapting one of said jointed means to be paid out as the other is simultaneously taken in on the oscillating movements of the supporting members, said 45 jointed means being unsecured intermediate their ends.

2. In a bucket, the combination with a plurality of oscillating supporting members, and a head to which said supporting members are pivotally connected, of a pair of 50 flexible means operatively connecting, movably, an opposing pair of supporting members, and holding means securing said flexible means to said members adjacent their 55 pivotal connections with the head adapting one of said flexible means to be paid out as the other is simultaneously taken in on the oscillating movement of said members, said flexible means being unsecured intermediate 60 their ends and free to move bodily lengthwise on such movement.

3. In a bucket, the combination with a plurality of oscillating supporting members, and a head to which said supporting members are pivoted, of a pair of linked mem- 65

bers having their respective opposite ends secured to the respective supporting members adjacent their pivotal axes on said head, and adapted to move bodily lengthwise in opposite directions on each oscillating movement of said supporting members, one of said linked members being paid out as the other is simultaneously taken in on the oscillating movement of said supporting members, and said linked members being unsecured intermediate their ends. 70

4. In a bucket, the combination with a plurality of supporting members, and a head to which said supporting members are pivotally connected, of linked members operatively connecting, movably, an opposing pair of supporting members, and holding means securing said linked members to said supporting members adjacent their pivotal axes on said head, in position to wind about 85 and to unwind from about said axes on the oscillating movements of said supporting members. 80

5. In a bucket, the combination with a plurality of oscillating supporting members, 90 and a head to which said supporting members are pivoted, of a pair of holding members on each of said supporting members adjacent the axes of the pivotal connections of said supporting members with said head, 95 the members of each pair moving in opposite directions with each oscillating movement of said supporting members, and flexible means connecting said holding members on an opposing pair of supporting members, 100 said flexible means being adapted to be paid out and taken up by the respective holding members on the operating movements of the supporting members.

6. In a bucket, the combination with a 105 plurality of oscillating supporting members, and a head to which said supporting members are pivoted, of holding members connected to the pivoted ends of each of said supporting members at points spaced apart 110 about the axes thereof and having limited movement in opposite directions upon each oscillation of said supporting members, and a plurality of linked members, the opposite ends of which connect said holding members 115 respectively on an adjoining pair of supporting members.

7. In a bucket, the combination with a pair of pivoted members, turning on their axes in opposite directions, of linked members secured to the pivoted ends of said pivoted members in position to wind about and unwind from about the axes of said pivoted members. 120

8. In a bucket, the combination with a 125 pair of pivoted members, oscillating on their axes in opposite directions, of a pair of linked members, and means securing the ends of said linked members to the pivoted ends of said pivoted members, in position 130

to wind about and unwind from about the axes of said pivoted members.

9. In a bucket, the combination with a pair of pivoted members, pivoted to turn on their axes in opposite directions, of a pair of linked members, and means securing, in reverse position, the ends of said pair of linked members to the pivoted ends of said pivoted members, whereby said linked members move in opposite directions in winding about and unwinding from about the axes of said pivoted members.

10. In a bucket, the combination with a pair of pivoted members, oscillating on their axes in opposite directions, of bearing members carried by said pivoted members, having limited rotary movement about the pivotal axes of said pivoted members, and flexible members secured to and adapted to wind upon and unwind from said bearing members in the operating movement of said pivoted members.

11. In a bucket, the combination with a plurality of bowl sections, of a movable sheave-carrying member, pivoted members having operative connection with said bowl sections and with said sheave-carrying member and pivoted to the latter to move on separate axes, of jointed means having operative connection with an adjoining pair of said pivoted members and means securing said jointed means to the pivoted ends of said pivoted members in position to be paid out and taken up on the oscillating movements of said pivoted members, said jointed means being unsecured intermediate their ends.

12. In a bucket, the combination with a plurality of bowl sections of a movable sheave-carrying member, pivoted members having operative connection with said bowl sections and with said sheave-carrying member and pivoted to the latter to turn on separate axes, flexible members operatively connecting movably an opposing pair of said pivoted members, and holding means securing said flexible members to the pivoted ends of said pivoted members, in position to be paid out and taken up on the oscillating movement of said pivoted members, said flexible members being free to move bodily lengthwise on such movement.

13. In a bucket, the combination with a plurality of bowl sections, of a movable sheave-carrying member, pivoted members having operative connection with said bowl sections and with said sheave-carrying member and pivoted to the latter to turn on separate axes, and a plurality of linked members having their respective opposite ends secured to the respective pivoted ends of said pivoted members in position to move bodily lengthwise in opposite directions on each turning movement of said pivoted members.

14. In a bucket, the combination with a

plurality of bowl sections, of a movable sheave-carrying member, pivoted members having operative connection with said bowl sections and with said sheave-carrying member, and pivoted to the latter to turn on separate axes, of a pair of linked members, having their respective ends secured to the pivoted ends of the respective pivoted members in reverse position, whereby, on each turning movement of said pivoted members, the pair of linked members will move bodily lengthwise in opposite directions, winding about and unwinding from about the axes of said pivoted members.

15. In an excavating bucket, the combination with a plurality of oscillating supporting members and a head to which said supporting members are pivoted, of means for controlling and limiting the relative movement of the head and supporting members, said means comprising a holding member on each of said supporting members extending angularly to the pivotal axis thereof, another holding member thereon likewise disposed angularly to said pivotal axis said holding members having limited movement in opposite directions on the oscillating movement of the supporting members and linked members whose opposite ends connect the first and second named holding members of an adjoining set of supporting members, whereby movement may be permitted to one supporting member only and to the extent that movement is permitted to the other supporting member.

16. In an excavating bucket, the combination with a plurality of oscillating supporting members and a head to which said supporting members are pivoted, of means for controlling and limiting the relative movement of the head and supporting members, said means comprising a holding member on each of said supporting members extending angularly to the pivotal axis thereof, another holding member thereon likewise disposed angularly to said pivotal axis, said holding members having limited movement in opposite directions on the oscillating movements of the supporting members, and flexible members whose opposite ends connect the first and second named holding members of an adjoining set of supporting members, whereby movement may be permitted to one supporting member only and to the extent that movement is permitted to the other supporting member.

17. In an excavating bucket, the combination of a head, a plurality of bowl sections, supporting members pivotally connecting said bowl sections and said head, a sheave-carrying member, pivoted means connecting said bowl sections with said sheave-carrying member at opposite sides of the latter in spaced apart relation, bearing members carried by said pivoted means having limited

rotary movement about the pivotal axis of the said pivoted means, and flexible members secured to and adapted to wind upon and unwind from the oppositely disposed bearing members when the bowl sections are opened and closed.

18. In an excavating bucket, the combination of a head, a plurality of bowl sections, supporting members pivotally connecting said bowl sections and said head, a sheave-carrying member, pivoted members secured to said bowl sections and pivoted to said sheave-carrying member at opposite sides of the latter in spaced apart relation, a pair of flexible members connected to opposing supporting members at their pivotal connection with said head, a pair of flexible members connected to said pivoted members at their pivotal connection with said sheave-carrying member, and means on said supporting members and on said pivoted members whereby the respective flexible members may be wound and unwound from about the pivotal axes of one set of supporting members and of one set of pivoted members while being unwound from and wound about the pivotal axes of the opposite set of supporting members and of the opposite set of pivoted members.

19. In an excavating bucket, the combination of a head, a plurality of bowl sections, supporting members pivotally connecting said bowl sections and said head, a sheave-carrying member, pivoted members connecting said bowl sections with said sheave-carrying member at opposite sides of the latter in spaced apart relation, bearing members in sets of two carried by each of said pivoted members, the sets of one pivoted member opposing the sets of the other pivoted member each having limited rotary movement in opposite directions about the pivotal axis, and a plurality of flexible members connecting the bearing members of opposite sets, the ends of said flexible members being secured to the bearing members of one set in positions the reverse of their positions on the other set and being secured to adjoining bearing members of each set in reverse position, whereby said flexible members will wind and unwind upon and from the bearing members of opposing sets in reverse direction as the bucket opens and closes.
